UNITED STATES PATENT OFFICE.

ABEL ROSE AND WARREN C. MAGEE, OF CLEVELAND, OHIO.

GARMENT-MARKING DEVICE.

Application filed March 7, 1921. Serial No. 450,119.

To all whom it may concern:

Be it known that we, ABEL ROSE and WARREN C. MAGEE, citizens of the United States, residing at Cleveland, in the county of Cuyahoga and State of Ohio, have invented certain new and useful Improvements in a Garment-Marking Device, of which the following is a specification.

This invention is primarily designed for 10 the use of tailors and dressmakers, being particularly adapted to mark a skirt or other garment instantaneously in a circle while it is being fitted or suspended from a person or a form. The marking medium is in 15 the form of a fine powder, and compressed air is used to jet the powder in spots upon the garment. By adjusting the marker vertically a circular line of spots may be marked in a true horizontal plane at different 20 distances from a given base, and to obtain a responsive movement and an accurate setting of the marker a counter balance is connected to the marker by means of a flexible measuring tape.

25 In the drawing accompanying this application, Fig. 1 is a horizontal elevation, and Fig. 2 a vertical section of the device. Fig. 3 is a perspective of a portion of the suspensory measuring tape, and Fig. 4 a sectional view of a portion of the marking tube.

The inventive concept as exemplified herein comprises a base member 2 having a round tubular standard 3 at one side thereof. Base 2 may be solid and made in any desired shape, but as shown it is in the form of a hollow ring and made of metal, preferably aluminum, and has a boss 4 adapted to receive the round tube 3. The upper end of this tube is provided with a combined 40 cap and pin tray 5, and a roller or sheave 6 is journaled within the upper end of the tube opposite a central opening 7 in the cap or tray. A weight 8 is free to slide vertically within tube 3 and is suspended by 45 a steel strap 9 from roller 6, and one side of this strap is provided with a tape measure 10 which may be read through sight opening 7 at all times. Strap 9 passes around a second sheave or roller 11 and thence downward to where it is attached to the sleeve 12 of a tubular marking ring 13 corresponding approximately to the diameter of base ring 2. Sleeve 12 is freely slidable upon the tubular post or standard 3 and a binding 55 action is prevented by attaching the strap 10 to the sleeve between the ring and the

post, the weight 8 serving as a counterpoise for the marking ring.

The inner circumference of the marking ring is provided with a number of small 60 orifices 14 evenly spaced at close intervals and open to the hollow interior of the ring within which a very fine powder may be placed through stoppered openings 15 at the top side of the ring. The interior bottom side of the ring may be scalloped or ribbed transversely to pocket small portions of the powder opposite each orifice 14, and a rubber bulb 16 affixed to a nipple 17 at one side of the ring provides a simple means 70 for compressing the air within the ring whenever marking is to take place. Thus a quick compression of bulb 16 will create a sudden inrush of air into the marking ring and cause a small amount of powder to be 75 jetted through each orifice 14, and when the bulb is released and assumes its normal shape a suction is created which clears the orifices of powder.

In use the marking ring is lowered or 80 brought close to the base and the person wearing the skirt to be marked steps into the ring and takes a central position in respect thereto. The marking ring is then raised to the desired height and in encircling 85 relation to the bottom edge of the skirt, and the bulb compressed, care being taken that the person is standing in a natural and upright position. The powder jetted through the openings in the ring marks the garment clearly and distinctly and evenly and the operation takes but an instant without the slightest inconvenience or fatigue to the wearer of the garment, and by lowering and raising the marking ring, the operation 90 can be repeated at another point in perfect parallel alignment with the first mark. If desired, the powder may be placed within the bulb 16, or in lieu of a bulb 16 any equivalent device may be used which will 95 create a sudden pressure within the ring or cause the powder to be jetted through the orifices or slots radially toward the center of the ring. However, it should be understood that only a small amount of powder 100 is discharged, preferably merely enough powder to make a distinct spot or mark, consequently the interval of flow of the air and powder is very limited and the amount of powder discharged is only approximately 105 the amount which would collect within each orifice.

110

What we claim is:

1. A device for marking garments, comprising a single tubular standard, a hollow perforated ring carried by and vertically adjustable upon said standard, a counterweight for said ring adapted to slide within said standard, a suspensory connection between said counterweight and ring supported by said standard, and a bulb associated with said ring adapted to force a powder into said ring to effect marking of a garment simultaneously at a plurality of points opposite the inner circumference of said ring where perforated.
- 15 2. A device for marking garments, comprising a tubular standard and a marking ring slidably supported upon said standard, a tape measure connected with said ring at one side of said standard, a sheave at the 20 top of said standard for said tape measure,

and a counterweight supported within said standard by one end of said tape measure.

3. A device for marking garments, comprising a base member having a tubular standard at one side thereof, a sheave with- 25 in the upper end of said standard, a tubular ring slidably mounted upon said standard and having a series of orifices at its inner circumference, an air compressing bulb connected with said ring, a counterweight with- 30 in said standard, and a flexible connection passing over said sheave and connected at one end to said counterweight and at the other end to said ring.

Signed at Cleveland, in the county of 35 Cuyahoga and State of Ohio, this 5th day of March, 1921.

ABEL ROSE.
WARRREN C. MAGEE.
